ATTORNEY

UNITED STATES PATENT OFFICE.

WILLIAM E. RAWLINGS, OF SANTA CLARA COUNTY, CALIFORNIA.

BED CANOPY.

Application filed January 26, 1927. Serial No. 163,754.

This invention relates particularly to that type of bed canopy designed to fit in a window opening when the lower sash is raised, whereby the occupant of the bed may be shut off from the air of the room in which the bed is situated and have an abundant supply of fresh air from the exterior of the building.

It is one object of the invention to provide a device of the character indicated that may be quickly and easily collapsed for transportation and expanded to fit in a window frame.

It is another object of the invention to provide a device of the character indicated that may be readily attached to a window frame without the use of screws or any device that will injure the said frame. It is also an object of the invention to provide a device of the character indicated that will be economical to manufacture, simple in construction and operation, light in weight, and highly efficient in its practical application.

In the drawing:

Figure 1 is a perspective illustration of my improved canopy mounted in a window frame, parts being broken away.

Figure 2 is an enlarged detail section on line 2—2 of Figure 1.

Figure 3 is an enlarged detail section on line 3—3 of Figure 1.

Figure 4 is a detail plan view of a portion of the frame when assembled.

Referring now more particularly to the drawing, I show at 1 a portion of the canopy frame comprising a bar jointed as at 1^a for adjustment and having end portions hinged as at 2^a and 3^a whereby they may be swung into parallel relation to each other as at 2 and 3, these ends being perforated as at 4. Arranged in each part 1, 2 and 1, 3 is a spring 5 having its one end mounted on the central part of part 1 and its other end extending along the inner surfaces of the adjacent part 2 and 3 and bearing thereagainst whereby to force the two parts 2 and 3 in opposite directions to each other.

At 6 are shown supporting bars having adjustable connection with parts 2 and 3 by means of bolts as 7 engaging the perforations 4. On the free ends of the bars 6 are mounted shoes as at 8 adapted to engage the guideways 9 in the window frame 10. On the bars 6 and adjacent the shoes

8 are mounted vertical bars 11 by means of 55 pivots 12, whereby to space the frame from the stool the desired distance, these bars or legs 11 being provided with buttons as 13 by means of which a canvas or covering 14 may be secured in place.

On the lower end of each bar 11 is secured a foot 15 extending laterally a distance as at 16 to engage the inner surface of the window frame, and thence backwardly and outwardly as at 17 to engage the outer surface of the window casing and resting upon the window stool 18 as shown. Connected to the lower end of each leg 11 is a brace bar 19 by means of pivot 20, the bar being attached to supporting bar 6 by the 70 adjustable fastening 7.

When it is desired to use the canopy it is only necessary to unfold the various parts connecting the bars 6—6 to the parts 2 and 3, straightening out the legs 11, and securing the braces 19 in position, after which the covering 14 is placed in position and buttoned as described. The engagement of the shoes 8 with the guides 9 under pressure of the spring 5 effectually holds the upper 80 portion of the device against displacement, and the legs 11 with their bottom parts 17 and braces 19 effectually supports the canopy in the desired extended position.

It is to be understood, of course, that while I have herein shown and described but one specific embodiment of the invention, changes in form, construction, and method of operation may be made within the scope of the appended claims.

I claim:

1. A canopy of the character described, comprising a collapsible frame, window frame engaging shoes mounted thereon, resilient means for urging said shoes into engagement with said frame, legs mounted on said frame adjacent said shoes adapted to engage the window stool and casing, and brace elements connecting the legs and frame.

2. A canopy of the character described, comprising a frame, window frame engaging shoes mounted thereon, resilient means for urging the shoes into engagement with the frame, legs mounted on the frame adjacent said shoes, feet mounted on the legs and formed to engage the window stool and both the side edge and face of the win-

dow casing, braces extending from the legs to the frame, and a cover for the frame.

3. A canopy of the character described, comprising a collapsible frame including a collapsible bar having end portions hingedly mounted thereon, resilient means for urging the end portions in opposite directions, extension bars adjustably mounted on said

end portions, window frame engaging shoes mounted on the extension bars, legs mounted on said frame adjacent said shoes adapted to engage the window stool and casing, and brace elements connecting the frame and legs, and a cover for the frame.

WILLIAM E. RAWLINGS.
